PACKAGE TYING MACHINE

Wolfgang Hermann, Chicago, Ill., assignor to
Chicago Printed String Co., Chicago, Ill., a cor-
poration of Illinois

Application January 26, 1933, Serial No. 653,647

31 Claims. (Cl. 100—31)

This invention relates to a package tying machine and concerns itself with an apparatus that winds some tying element such as ribbon, string or tape around the package and ties or fastens the same with a metal clip that is formed in the apparatus and applied to the tying element after it has been wrapped around the package.

The invention comprises the novel structure and combination of parts hereinafter described 10 and more particularly pointed out and defined in the appended claims.

In the accompanying drawings which illustrate a preferred form of this invention and in which similar reference numerals refer to similar features in the different views:

Figure 1 is a side elevational view of a tying machine involving this invention.

Figure 2 is a top plan view of the machine.

Figure 3 is a plan view of the machine with the 20 table or platform removed.

Figure 4 is a sectional view taken upon the line IV—IV of Figure 3 looking in the direction of the arrows.

Figure 5 is an enlarged sectional view taken 25 upon the line V—V of Figure 3 looking in the direction of the arrows.

Figure 6 is a sectional view taken upon the line VI—VI of Figure 3 looking in the direction of the arrows.

Figure 7 is a sectional view taken upon the line VII—VII of Figure 3 looking in the direction of the arrows.

Figure 8 is a sectional view taken upon the line VIII—VIII of Figure 3 looking in the direction 30 of the arrows.

Figure 9 is a sectional view taken upon the line IX—IX of Figure 3 looking in the direction of the arrows.

Figure 10 is a sectional view taken upon the 40 line X—X of Figure 3 looking in the direction of the arrows.

Figure 11 is an enlarged elevational view of the clip crimping mechanism.

Figure 12 is an enlarged sectional view taken 45 upon the line XII—XII of Figure 8 looking in the direction of the arrows.

Figure 13 is a bottom plan view of the table or 50 platform illustrating certain features of the machine attached thereto.

The machine or apparatus herein disclosed 55 comprises a plurality of castings 1, 2 and 3 which are arranged in parallel spaced relation to constitute three supporting walls for the parts of the machine. These castings are adapted to rest upon a table or some suitable support. Upon the top of these castings there is screwed a table 4 having a slot 5 (Figure 13) extending inwardly from its outer end to a distance substantially midway of the table for receiving the tying element 6 which is wound upon a reel 7 which is

mounted upon a shaft 8 (Fig. 2) supported upon a standard 9 attached to the far ends of the castings 1 and 2. A sleeve 10 having a flanged end 10a for engaging one end of the reel has a bayonet slot 11 thru which a screw 12 of the shaft 8 extends. A coil spring 13 surrounds the shaft 8 and normally bears against the end of the sleeve 10. The screw 12 is normally in the straight portion of the slot 11 so that the sleeve 10 can slide upon the shaft and offer a certain amount of frictional resistance to the reel. The sleeve 10, however, can be slid until the screw registers with the offset in the slot when the sleeve may be rotated to bring the screw into such offset position of the slot and out of functional contact with the reel. This may be desirable when the reel is removed for some purpose.

A standard 14 (Figure 1) is attached to the far end of the casting 3. The upper end of this standard is in the form of a bifurcated bearing 14a (Figure 2) in which a shaft 15 is journaled. A small pinion 16 is secured upon said shaft in the bifurcation of said bearing for operating said shaft as will later more fully appear. A collar 17 is secured upon the shaft and a coil spring 18 surrounds said shaft between said collar and bearing 14a. One end of this spring is anchored in the bearing and the other end is anchored in the collar with the result that said spring is wound up or put under tension when the shaft 20 rotates clockwise as viewed in Fig. 1.

A tensioning device 19 (Figures 1 and 2) that bears against the tying element which, in the present instance, is shown as a ribbon on the reel 7, is loosely mounted upon the shaft 15. 35 The free end of the ribbon tensioning device is bifurcated and the arms 19a thereof are journaled upon the shaft 15. A coil spring 20 which surrounds the outer end portion of the shaft 15 has one end anchored to a collar 21 secured upon 40 said shaft and the other end engaging the tensioning device 19 for yieldingly pressing said device against the ribbon. Secured upon the shaft 15 between the arms 19a of the tensioning device, there is a curved ribbon guide arm 22 provided upon its upper edge with suitable keepers 23, 24, 25, 26, 27 and 28 for retaining the ribbon which is threaded through these keepers as it passes from the reel. The end of the ribbon projecting from the end of the guide arm 22 is held 45 by one of the clamping blades 29 (Figures 5 and 10) of a rotatable clamping device mounted upon a shaft 30 journaled in the walls 31 and 32 of a casting 33 attached to the castings 1 and 2. A clamping spring 34 is attached to the wall 32 and 50 has an outwardly offset portion 34a overlapping the circular path of the blades 29. The ribbon may be initially attached to one of the blades 29 in any suitable manner, and after a package has 55 been wrapped and the ribbon has been severed 60

by a shearing element 35 secured upon the shaft 30 upon the opposite side of the wall 32 thru rotation of the shaft, the end of the ribbon will again be automatically clamped as will later more 5 fully appear. It might be mentioned that the shearing element 35 is a counter part of the rotatable clamping device and has four cutting blades that register with the clamping blades 29. These cutting blades cooperate with a shoulder 10 36 upon the wall 32 under which the ribbon passes.

In order to clearly understand the operation of the clamping blades and shearing element it will be necessary to describe the manner of tying the ribbon around a package. In referring to 15 Figure 1, it will be noted that the ribbon extends from the reel to the arm or neck 22, over such arm and down thru the slot 5 in the table and to the clamping device. In the slot there is a bridging member 37 (Figure 13) which limits the 20 inward movement of the ribbon in the slot and which is secured upon a slide 38 upon the bottom of the table. This slide has a plurality of slots 39 thru which screws 40 pass that are secured 25 in the table whereby the slide is slidably mounted. A coil spring 41 anchored to the slide and to the table tends to project the bridging member across the slot. A bolt or rod 42 extends downwardly from the slide for operating the same.

30 The package 43 (Figure 9) to be tied is placed upon the table 4 against the adjustable guides 44 and 45 and beneath the downwardly inclined portion of the ribbon 6 between the table and the end of the arm 22 when the same is in the position shown in Figure 1. When the package is 35 pushed back against the guide or stop member 44, the ribbon will of course be unwound from the reel. When the package has been positioned upon the table as just described and the machine 40 put in operation, the arm 22 will swing downwardly into the position that is shown in Figure 9 and the ribbon 6 will be tightly drawn around the package. In this position of the parts, it will be 45 noted that the portion of the ribbon from the clamping device to the stop 37 is located under the shoulder 36 while the portion between the front end of the package and the end of the arm is also located beneath the shoulder 36 just slightly below the first mentioned portion. In this 50 position of the parts, a metal clamp is applied to the three portions of the ribbon below the package, namely the two portions just mentioned and the portion of the ribbon above the table as will later appear.

55 The metal clamp for tying the ribbon is formed in the machine. To this end there is provided a reel 46 (Figures 1, 3 and 7) for containing a roll of metal in the form of a band. From the reel 46, the metal band passes around a guide sleeve 60 (not shown) journaled upon a bolt 47 passing thru a guide support 48 secured in the casting 3. The guide support 48 carries a pressure roll 49 that cooperates with a feed roll 50 journaled upon a stub shaft 51 extending from and 65 supported by the casting 3. This feed roll 50 has a hub provided with ratchet teeth 52 shown in dotted lines in Figure 7. A pawl 53 mounted upon a lever 54 engages said teeth for rotating said feed roller. The pawl lever 54 is pivoted intermediate its ends to the casting 3 as indicated at 55 and the power arm of this lever is provided with a roller 56 in engagement 70 with a cam 57 mounted upon a shaft 58 journaled in said castings and operated as will later be set forth. The roller support 48 is provided

with a rod 59 having a shoulder end 60. A rod 61 which is secured at its upper end to a support 62 on the casting 3 passes thru an aperture in the shouldered end of the rod 59. A coil spring 63 surrounds the rod 61 between the support 62 and the rod 59 for exerting a yielding force upon the rod 59 and roller 49. A nut 64 upon the lower end of rod 61 engages the arms 59 and may be used to disengage the first rollers for loading the metal band.

10 The metal band passes between the rollers 49 and 50 and is fed by the roller 50 between cutting die block 65a and guide block 65b in a die box 65 supported by the casting 3. Within the die box there is a stationary male forming die member 66 having an inner reduced rectangular portion 67. Cooperating with the male die there is a moveable female die member 68 having a recess 69 for receiving said rectangular portion 67, a shoe 68a acting as a stop for the metal band, and a cutting edge 68b adjacent block 65a for severing the metal band. A plunger 70 is slidably mounted in the die member 68 and is provided at one end with a head 71 and at the other end with a head 72 located in an enlarged bore 73 in the female die member. A coil spring 74 located in the bore bears against the head 72 at one end and against a screw plug 74a at the other end. A roller 75 is journaled in the end of die member 68 and adapted to be actuated by the cam 57 for moving the female die member. When the female die member is actuated by the said cam, cutting edge 68b severs the metal band against cutting edge 65c on the upper inner edge of block 65a and a channel like clamp is formed by recess 69 over rectangular portion 67, the plunger 70 being depressed during the movement. When the cam 57 disengages the roller 75, the spring 74 will project the plunger for ejecting the clamp from the recess in the female die and holding it 20 on the rectangular portion 67 of the male die until ejected.

30 Mechanism has been provided for ejecting the formed clamp from the die box. This mechanism is shown in Figure 3, and consists of a bell crank 45 lever 76 pivoted at its apex to a support 77 extending from the casting 3, and provided upon its power arm with a roller 78 adapted to be actuated by the cam 57. A slide 79 has a lost motion connection with said lever and this slide 50 normally extends a distance into the die box and when it is actuated it will project the formed clamp from the die box. A leaf spring 80 is fastened to the support 77 and engages a pin 81 upon said lever for retracting the slide 79 after 55 each actuation thereof. The slide 79 is preferably supported beyond the die box in a guide way formed by a pair of members 82 and 83 (Figure 1).

Upon the inner side of the die box, there is a discharge guide way 84 for the clamps. This 60 guide way is formed by a pair of parallel members 85 and 86 attached to the inner wall of the die box. A number of formed clamps are always in this 65 guide way, the slide 79 moving the entire row of clamps, so that the forward clamp will be projected between a pair of movable jaw members 87 and 88 (Figures 11 and 12). These jaw members have spaced teeth 88a that interfit when the jaw members are moved together. Coil springs 89 between the jaw members normally tend to 70 separate the same. These jaw members are located between a pair of guide plates 90 and upon the top of a support 93. These guide plates have upper rectangular recesses 91 corresponding to the recesses between the jaw members in their 75

normal open position. A cross member 92 is attached to the lower margin of each side plate and these plates are attached to the support 93 which slidably carries a conical cam 94. The cross members 92 project beyond the side edges of the plates 90 and to the projecting ends are pivoted levers 95 intermediate their ends. The upper ends of these levers are designed to engage the jaw members, which have arcuate outer portions 10 so the levers can readily move relative thereto. The lower ends of said levers are designed to be engaged by the cam 94.

The support 93 is attached to an elbow-like lever member 96 which is secured upon a rotatable shaft 97 supported by the castings 2 and 3. This elbow lever is adapted to be elevated until arrested by an adjustable stop 98 threaded in a lug 99 on the casting 3. When the elbow shaped lever has been thuswise elevated, the clamping jaws 15 will be in position to apply the clamp to the ribbon. During this movement of the jaw members, a curved leaf spring 100 attached to the hub of the elbow shaped lever will guide the different portions of the ribbon into the clamp 101 carried 20 by the jaw members as shown in Figure 6. In addition a pair of sloping slide fingers 102 slidably mounted upon the bottom of the table are adapted for pressing the upper part of the ribbon into the clamp.

30 The slide fingers 102 are best shown in Figures 8 and 13, and it will be noted that they are attached to the edges of a slide plate 103 which is provided with a pair of slots 104 thru which screws 105 extend that are threaded in said table. With 35 reference to Figure 8, it will be noted that these fingers have upwardly offset portions 102a which extend in suitable slots in the table and these offset portions have downwardly sloping ends 102b which are adapted to engage the ribbon and move it downwardly when the slide is actuated. 40 It will be noted that a suitable opening 106 has been provided in the table for this purpose.

The slide 103 is normally held in its inoperative position by a spring 107 anchored at one end to the slide and at the other end to the table. The 45 slide 103 is connected to an actuating member 108 which is slidably mounted upon the bottom of the table by a pin 109 and slot 110 arrangement. A cross member 111 connects the actuating member 50 with the slide 103. The actuating member 108 has a pendant end 112 which lies in the path of a screw 113 (Figure 8) upon the hub of the elbow shaped lever 96 with the result that when such lever has been substantially elevated, the 55 screw 113 will strike the pendant portion 112 and slide the actuating member 108 and the slide 103 with its fingers for depressing the ribbon into the clamp.

When the ribbon has been guided and depressed into the metal clamp as just described, a lever 114 (Figure 11) will be actuated for engaging the bottom of the cam 94 and elevating the same for operating the levers 95 and partially closing the jaw members 87 and 88 for 60 clamping the metal clamp upon the three parts of the ribbon.

When the metal clamp has been applied, the 65 forementioned shaft 30 is rotated to cause a cutting blade to rotate upwardly and sever the two lower overlapping strands of the ribbon. At the same time, the clamping blades 29 will rotate and one blade thereof will engage the portion of the ribbon extending from the arm 22 to the left of the shearing element as viewed in Figures 9 and 70 75 10 and move under clamping spring 34 and cause

the ribbon to become wrapped thereon. Thereafter, the parts will be returned to initial position for another operation.

The mechanism for operating the different parts will now be set forth. A motor 115 is suitably supported upon the castings 1 and 2 and the shaft of this motor carries a pinion 116 (Figure 3) which meshes with an idler gear 117 journalled upon a shaft 118 supported upon a bracket 119 attached to the casting 1. The gear 117 has a 10 pinion 120 secured thereto which drives a large gear wheel 121 journalled upon a stub shaft 122 journalled in a bearing upon the casting 1. The gear 121 has a pinion 123 secured thereto which drives a large gear wheel 124 on the main driving 15 shaft 58 which is journalled in the castings 1, 2 and 3.

The first mechanism on shaft 58 that will be described is the mechanism for periodically rotating shaft 30 and is shown in Figure 4. It will 20 be observed that a cam 125 is secured upon the shaft 58 and actuates a lever 126 pivoted intermediate its ends to the casting 1 as indicated at 127. A link 128 is pivotally connected to the free end of the lever 126, and to a lever 129 journalled upon the shear shaft 30. A pawl 130 is pivotally carried by the lever 129 and engages a ratchet wheel 131 secured upon the shaft 30. A coil spring 132 surrounds the shaft 30 and bears 25 against an adjustable collar 133 upon said shaft and against the hub of the clamping device. This spring tends to maintain the clamping device and shear against the forementioned wall 32. A coil spring 134 connected to the casting 1 and to the lever 128 maintains said lever in engagement with the cam 125. The cam 125 has a cam portion 30 35 125a that actuates the lever once during each rotation thereof.

Just to the right of the cam 125, there is another cam 135 (Figure 5) upon the shaft 58. This cam actuates a lever 136 having a roller 137 engaging the same. This lever 136 is pivoted upon a stud 138 secured upon the casting 2. The lever 136 comprises a segment gear 139 which is welded 40 or attached to the actuated part thereof. The segment gear 139 meshes with a pinion 140 secured upon the forementioned shaft 97 which elevates the clamp holder. A coil spring 97a (Figure 3) surrounds the shaft 90. One end of the spring 45 engages a pin 97b projecting from the casting 2. The other end of the spring is anchored to the hub of the elbow shaped lever or clamp holder. The spring tends to force the clamp holder downwardly.

The next operating mechanism on shaft 58 is best shown in Figure 6 and comprises a cam 141 which engages a roller 142 secured intermediate the ends of a lever 143 which is pivoted at its forward end to the casting 2 upon a pivot stud 144. 60 The rear end of the lever 143 engages a vertical rack bar 145 that extends into the bearing 14a on the standard 14 and rotates the pinion 16 for lowering the ribbon guide arm 22. Coil spring 146 which rests upon the base of the standard 14 65 surrounds the rack bar 145 and abuts a collar 147 thereon to cushion and limit the downward movement of said rack bar. When said rack bar is elevated by the lever 143, the coil spring 18 on shaft 15 is put under tension with the result that 70 said spring 18 will rotate said shaft in a reverse direction for elevating the guide bar 22 when the cam 141 presents a receding portion thereof to said lever and allows the rack bar to descend.

Adjacent the cam 141, there is an arm 148 rigid- 75

ly secured upon the shaft 58. A roller 149 is mounted upon the end of the arm 148. The arm 148 rotates with the shaft 58 in an anti-clockwise direction as viewed in Figure 6. When the 5 elbow shaped lever 96 that is secured upon the shaft 97 has been elevated and the ribbon has been guided into the metal clamp, the said arm 148 will have rotated into position to engage the surface 150 (Figures 6 and 8) of a triangular 10 shaped cam pivotally mounted upon the elbow shaped lever 96 as indicated at 152. The opposite face of the cam engages the aforementioned lever 114 which, it will be noted, is also pivoted upon the clamp or elbow shaped lever 96 as indicated at 153.

The said arm 148 will eventually rotate past the triangular cam and move upwardly and engage the peg 42 and the slide 38 for retracting the slot bridging element 37 as shown in dotted lines in 20 Figure 13 for releasing the tied ribbon which is formed with a loop through which such bridging element extends.

In its inoperative position, the parts of the machine are in the positions shown in Figure 1 with 25 the ribbon 6 anchored by a blade 29 of the rotatable clamping device and a package on the table. If the motor is now started, the shaft 58 with its cams will be rotated and the rack bar 145 will be elevated first for causing the arm 22 to rotate 30 downwardly into the position shown in Figure 9 for tying the ribbon tightly around the package. At this point in the operation, the cam 135 will have rotated into position for actuating the gear segment 139 for rotating the shaft 97 and elevating the clamping jaws which have been supplied with a metal clamp in the meantime by the slide 76. It will of course be understood that a metal clamp is also formed during this interval as previously set forth. When the jaws have been 40 elevated the parts of the ribbon will be guided into the clamp by the spring 100 and the slide fingers 102, and at this point the arm 148 will have rotated into position to actuate the triangular cam 151 for actuating lever 141 for raising 45 the cam 94, thereby separating the lower portions of the levers 95 and closing the jaws for clamping the metal clamp upon the ribbon. When the arm 148 rotates past the cam 151, the springs 89 will expand the jaws and return the 50 parts to their original position. At about this time, the cam 125 will rotate into position for imparting a partial rotation to shaft 30 through the aforescribed ratchet mechanism for rotating the shearing element and severing the ribbon. At 55 the same time, the ribbon clamp is rotated for clamping the end of the ribbon as previously explained. During this period, the arm 148 will have rotated into position to actuate the slide 38 for causing the bridging element 37 to release the 60 ribbon or tape. As the motor continues to rotate and the different cams rotate to inoperative positions, the different springs will return the guide arm and the jaw lever to original positions, and at the end of a revolution of the drive shaft 58, an 65 automatic clutch will be thrown out for stopping the rotation of the shaft 58. This automatic clutch has not been shown as such clutches or stop mechanisms are common and well-known.

I am aware that many changes may be made 70 and numerous details of construction may be varied through a wide range without departing from the principles of this invention, and I, therefore, do not purpose limiting the patent granted herein otherwise than necessitated by the prior art.

75 I claim as my invention:

1. In a packaging machine, a package supporting table having a slot, a slidable bridging element extending across said slot extending inwardly from one margin, a ribbon reel supported above said table, a curved ribbon guide arm pivoted above said table, means on said guide arm for retaining the ribbon thereon for its entire length, said ribbon adapted for extension through said slot, means for anchoring the end of said ribbon projecting from said arm, means for rotating said 10 arm to bring a portion thereof below said table for wrapping the ribbon around the package, a clamp holder, means for moving the clamp holder adjacent the ribbon, means for forcing the ribbon into said clamp holder, means for actuating the 15 clamp holder after it has received said ribbon, and means for severing said ribbon and clamping the end projecting from said arm beneath said table.

2. In a package tying machine, a swingable 20 lever, clamping mechanism thereon, a pair of levers for actuating said clamping mechanism, a cam for engaging said levers, a cam actuating lever pivoted upon the first mentioned lever and means for actuating said cam actuating lever. 25

3. In a package tying machine, a package supporting table, a standard above said table, a ribbon reel supported upon said standard, a second standard above said table, a ribbon guide arm mounted upon said second standard, and tension 30 means responsive to the movement of said guide arm for frictionally engaging the ribbon on said reel.

4. In a package tying machine, the combination with means for wrapping a tying element 35 around the package, of a metal clamp holder, means for supplying a metal clamp to said holder, means for elevating said holder for receiving the tying element, a pair of bevelled slides, means for mounting said slides adjacent the tying element 40 and means for operating said slides for guiding and forcing said tying element into said clamp.

5. In a packaging machine, a package supporting table having a slot extending inwardly from a margin thereof, a tying element reel, a guide arm 45 for the tying element pivoted above said table and movable into position beneath said table with said tying element extending through said slot, means movable to bridge said slot for periodically limiting the inward movement of said tying element therein, means for anchoring the end of said tying element projecting beyond said arm, a clamp holder, means for moving said clamp holder adjacent the tying element, means for forcing the tying element into said clamp holder and 55 means for actuating said clamp holder after receiving said tying element to secure a clamp on said tying element.

6. In a packaging machine, a package supporting table having a slot extending inwardly from a margin thereof, a tying element reel, a guide arm for the tying element pivoted above said table and movable into position beneath said table with said tying element extending through said slot, means movable to bridge said slot for periodically limiting the inward movement of said tying element therein, means for anchoring the end of said tying element projecting beyond said arm, a clamp holder, means for moving said clamp holder adjacent the tying element, means for forcing the tying element into said clamp holder, means for actuating said clamp holder after receiving said tying element to secure a clamp on said tying element and means for severing said tying element 75

and again anchoring the severed end thereof projecting from said arm beneath said table.

7. In a package tying machine, a package supporting table having a slot extending inwardly from one margin thereof, a reel for carrying a tying element, means mounted below said table for anchoring an end of said tying element, a guide arm for said tying element pivotally mounted on said table and movable in the plane of said slot from a position with its end above said table to a position with its end below said table, a member slidably transversely of said slot to limit the movement of said tying element inwardly of said slot, means for moving said guide arm to wrap said tying element about a package, a reel for metallic ribbon, means for forming clamps from said ribbon, means for receiving said formed clamps and applying said clamps to said tying element, means for severing said tying element and again anchoring a fresh end thereof and means operative to withdraw said slidable member from across said slot to permit the removal of the tied package.

8. In a package tying machine, a package supporting table having a slot extending inwardly from one margin thereof, a reel for carrying a tying element, means associated with said reel for tensioning the tying element during its unwinding therefrom, means mounted below said table for anchoring an end of said tying element, a guide arm for said tying element pivotally mounted on said table and movable in the plane of said slot from a position with its end above said table to a position with its end below said table, a member slidably transversely of said slot to limit the movement of said tying element inwardly of said slot, means for moving said guide arm to wrap said tying element about a package, a reel for metallic ribbon, means for forming clamps from said ribbon, means for receiving said formed clamps and applying said clamps to three strands of said tying element including two strands forming a loop about said slidable element, means for severing said tying element and again anchoring a fresh end thereof and means operative to withdraw said slidable member from across said slot to permit the removal of the tied package.

9. In a package tying machine, a package supporting table having a slot extending inwardly from one margin thereof, a reel for carrying a tying element, means mounted below said table for anchoring an end of said tying element, an arcuate guide arm for said tying element pivotally mounted on said table and movable in the plane of said slot from a position with its end above said table to a position with its end below said table, a member associated with and movable across said slot to limit the movement of said tying element inwardly of said slot, means for moving said guide arm to wrap said tying element about a package, a reel for metallic ribbon, means for forming clamps from said ribbon, means for receiving said formed clamps and applying said clamps to said tying element, means for severing said tying element and again anchoring a fresh end thereof and means operative to remove said member from across said slot to permit the removal of the tied package.

10. In a package tying machine, a package supporting table having a slot extending inwardly from one margin thereof, a reel for carrying a tying element, means mounted below said table for anchoring an end of said tying element, a guide arm for said tying element pivotally mounted

on said table and movable in the plane of said slot from a position with its end above said table to a position with its end below said table, a member slidably transversely of said slot to limit the movement of said tying element inwardly of said slot, means for moving said guide arm to wrap said tying element about a package, a reel for metallic ribbon, means for forming clamps from said ribbon, means for receiving said formed clamps and applying said clamps to said tying element, means for severing said tying element and again anchoring a fresh end thereof, means operative to withdraw said slidable member from across said slot to permit the removal of the tied package, a main drive shaft and means including cams for operating said various aforementioned means and slidable member in synchronism.

11. In a package tying machine, a package supporting table having a slot extending inwardly from one margin thereof, a reel for carrying a tying element, means mounted below said table for anchoring an end of said tying element, a guide arm for said tying element pivotally mounted on said table and movable in the plane of said slot from a position with its end above said table to a position with its end below said table, a member slidably transversely of said slot to limit the movement of said tying element inwardly of said slot, means for moving said guide arm to wrap said tying element about a package, a reel for metallic ribbon, means for forming clamps from said ribbon, means for receiving said formed clamps and applying said clamps to said tying element, means associated with said clamp receiving means to guide three strands of said tying element into a clamp applied thereto, means operative to cause said clamp receiving means to crimp said clamp about said strands, means for severing said tying element and again anchoring a fresh end thereof and means operative to withdraw said slidable member from across said slot to permit the removal of the tied package.

12. In a package tying machine, a package supporting table having a slot extending inwardly from one margin thereof, a reel for holding a tying element, a guide arm pivotally mounted on said table and movable in the plane of said slot, a tensioning device for keeping said tying element under tension, means beneath said table for anchoring an end of said tying element with a strand of said tying element passing through said slot and a member movable to extend across said slot to limit the inward movement of said tying element.

13. In a package tying machine, a package supporting table having a slot extending inwardly from one margin thereof, a reel for holding a tying element, a guide arm pivotally mounted on said table and movable in the plane of said slot, a tensioning device for keeping said tying element under tension, means beneath said table for anchoring an end of said tying element with a strand of said tying element passing through said slot, a member movable to extend across said slot to limit the inward movement of said tying element, means for severing said tying element and means for again anchoring an end thereof.

14. In a package tying machine, a package supporting table having a slot extending inwardly from one margin thereof, a reel for holding a tying element, a guide arm pivotally mounted on said table and movable in the plane of said slot, a tensioning device for keeping said tying element under tension, means beneath said table

for anchoring an end of said tying element with a strand of said tying element passing through said slot, a member movable to extend across said slot to limit the inward movement of said 5 tying element, means for clamping together strands of said tying elements, means for severing said tying element and means for again anchoring an end thereof.

15. In a package tying machine, a swingable 10 lever, a clamping mechanism carried thereby including jaw members having clamp engaging teeth, a pair of levers for actuating said jaw members, a cam for engaging said levers, a cam actuating lever pivoted upon said first mentioned 15 lever and means for actuating said cam actuating lever.

16. In a package tying machine, a swingable lever, a clamping mechanism carried thereby including jaw members having clamp engaging 20 teeth, springs tending to separate said teeth, a pair of levers for actuating said jaw members against the action of said springs, a cam for engaging said levers, a cam actuating lever pivoted upon said first mentioned lever and means 25 for actuating said cam actuating lever.

17. In a package tying machine, a package supporting table having a slot extending inwardly from one margin, a ribbon reel supported above 30 said table, a curved arm pivoted above said table and having keepers thereon for receiving the ribbon from said reel, said ribbon being adapted to extend beyond said arm and through said slot, a rotatable clamp below said table for anchoring the free end of said ribbon, means for 35 swinging said arm downwardly to bring the end thereof beneath the table for wrapping said ribbon around a package and for bringing a portion of said ribbon in underlapping relation with the anchored end portion to provide overlapping portions, means for applying a clamp to the overlapping portions of said ribbon, a cutter movable 40 with said rotatable clamp and means for rotating said clamp for shearing the lower two overlapping portions of said ribbon and clamping the sheared end extending from said arm.

18. In an automatic machine for tying a package, a table having a slot extending inwardly from one margin, a ribbon reel above the table, a curved ribbon guide arm pivoted above the 50 table and having means for receiving and guiding the ribbon, said ribbon being adapted to extend beyond the end of said arm and through said slot, means including a rotatable clamp for anchoring the end of said ribbon beneath the table, means for swinging said arm downwardly 55 for bringing the end thereof beneath the table and beyond said clamp to underlap a portion of said ribbon and to wrap the same around the package, means for applying a clamp to the overlapping portions of said ribbon, a shearing means associated with said rotatable clamp, and means for operating said rotatable clamp and said shearing means for shearing the two lower strands of said ribbon and anchoring the sheared 60 end projecting from said arm.

19. In a package wrapping machine, a table having a slot extending inwardly from one margin, a reel for holding a tying element mounted upon the table, a curved guide arm pivoted upon 70 the table and having means for receiving and guiding the tying element, said tying element being adapted to extend over the end of said arm and through said slot, a rotatable clamping member beneath said table, means cooperating 75 with said clamping member for clamping the

end of said tying element, a shearing mechanism including a shearing element rotatable with said clamping member and means for rotating said clamping member and shearing element for shearing said tying element and reclamping the 5 sheared end between said clamping member and said cooperating means.

20. In a package tying machine, a table having a slot extending inwardly from one margin, a reel for holding a tying element mounted 10 upon said table, a curved guide arm pivotally mounted upon said table and having means for receiving and guiding said tying element, said tying element being adapted to extend over the end of said arm and through said slot, clamping 15 means beneath the bottom of the table for anchoring the end of said tying element, means for lowering said arm for wrapping the tying element around a package and for moving the end of said arm beyond said clamping means 20 for causing the tying element extending therefrom to underlap the end portion of said tying element and the portion of the tying element upon the bottom of the package, means for applying a clamp to the three overlapping portions of said tying element and means for shearing the two lower overlapping portions of said 25 tying element.

21. In a package tying machine, a table having a slot extending inwardly from one margin, 30 a reel for a tying element mounted upon said table, a curved arm pivoted upon the table and having means for receiving and guiding said tying element, said tying element being adapted for extending beyond the end of said arm and 35 through said slot, a shaft mounted beneath said table, a clamping member comprising spaced radially extending blades secured upon said shaft, an abutment adapted for cooperation with one of said blades for clamping the end of the 40 tying element, a cutting element secured upon said shaft, means for lowering said arm for wrapping the tying element around a package and positioning the portion adjacent thereto in underlapping relation with the clamped end portion 45 and the portion at the bottom of the package, means for applying a clamp to said three portions and means for rotating said shaft for shearing the two lower portions of said tying element and clamping the sheared end extending 50 from said arm.

22. In a package tying machine, a rotatable shaft, a clamping member having radially extending blades secured upon said shaft, an abutment cooperating with said blades for clamping 55 the end of a tying element, a cutter secured upon said shaft adjacent said clamping member, and means for periodically rotating said shaft for severing the tying element and clamping the end 60 against said abutment.

23. In a package tying machine, a table having a slot extending inwardly from one margin, a reel for a tying element mounted upon said table, a curved arm pivoted upon the table, means upon said arm for retaining and guiding the 65 tying element lengthwise thereof, said tying element being adapted to extend over the end of said arm and through said slot and a distance rearwardly under the table, means for anchoring the end of said tying element beneath said 70 table, means for lowering said arm for wrapping the tying element around a package positioned upon the table against said tying element and for bringing the end of said arm beyond said clamping means for causing portions of said 75

tying element to overlap, a metal clamp holding device, means for supplying a metal clamp to said device, means for moving said device to engage said metal clamp with the overlapping portions of said tying element, means for crimping said metal clamp upon said overlapping portions, and means for shearing the two lower overlapping portions of said tying element.

24. In a package tying machine, a table having a slot extending inwardly from one margin, an actuatable bridging element extending across said slot, a reel for a tying element mounted upon said table, a curved arm pivoted upon said table and having means for receiving and guiding said tying element, said tying element being adapted to extend from the end of said arm and through said slot in front of said bridging element, means for clamping the end of said tying element beneath said table rearwardly of said bridging element, the tying element above said table being adapted to extend under a package and in registry with said slot and over the rear end and top thereof when said arm is in elevated position, means for lowering said arm to wrap the tying element over said package, said arm being lowered to bring the end thereof beyond said clamping means for causing the tying element adjacent the end thereof to underlap the portion of the tying element extending from said clamping means and the portion of the tying element at the bottom of said package, means for applying a clamp to the three portions of said tying element and means for shearing the two lower portions thereof.

35. 25. In a package tying machine, means for wrapping a tying element around a package with one end portion extended from the package and in underlapping relation with the portion of the tying element at the bottom of the package, 40 said means including a movable arm adapted for positioning a portion of the tying element in underlapping relation with the extended end portion, means for applying a clamp to the three portions of said tying element and means for 45 shearing the two remote portions.

26. In a package tying machine, a table having a slot extending inwardly from one end, means for anchoring a tying element beneath the table, said tying element extending upwardly through 50 said slot for extending partially around a package, means for wrapping the tying element around the package and extending a portion thereof beneath the table in underlapping relation with the anchored end, means for clamping the portions of 55 the tying element beneath the table to the portion surrounding the package and means for shearing the two portions beneath the table.

27. In a package tying machine, mechanism 60 for clamping one end of the tying element, means for wrapping an intermediate portion of the tying element around the package, said means including a movable member for positioning a portion of the tying element in underlapping relation with the anchored end portion and the portion on 65 the bottom of the package, a movable clamp holder, means for supplying a clamp to said holder, means for moving said holder in registry with the said portions of the tying element, means for forcing the three overlapping portions of the 70 tying element into the clamp in said holder,

means for crimping the clamp upon the three portions of said tying element and means for shearing the two outermost portions.

28. In a package tying machine, mechanism 5 for clamping one end of a tying element, means for wrapping an intermediate portion of the tying element around a package, said means including a movable member for positioning a portion of the tying element in underlapping relation with the anchored end portion, means for clamping the 10 two portions of the tying element to the portion surrounding the package and means for shearing the outermost portions.

29. In a packaging machine, the combination 15 with means for wrapping a tying element around a package and positioning portions thereof in overlapping relation, of a swingable clamp holder, means for supplying a metal clamp to said holder, means for swinging said clamp holder into position for receiving the overlapping portions of said tying element, slidable means for guiding said tying element into the clamp in said holder, said slidable means and clamp holder having coacting shoulders adapted for coming into engagement 20 upon movement of said clamp holder into position to receive said overlapping portions of said tying element, means for actuating said clamp holder for crimping the clamp upon said overlapping portions of said tying element and means for 25 shearing two strands of said overlapping portions. 30

30. In a packaging machine, the combination with means for wrapping a tying element around a package and positioning portions thereof in overlapping relation, of a combined clamp holder 35 and crimper, means for forming a metal clamp, means for transferring a formed clamp to said holder, said holder having a shoulder, slidable means for forcing the overlapping portions of said tying element into the clamp in said holder, said clamp holder having a shoulder, means for swinging 40 said clamp holder into position to receive the overlapping portions of said tying element and bringing said shoulders into engagement for actuating said slidable means, means for actuating said clamp holder for crimping said clamp around 45 the overlapping portions of said tying element and means for shearing said tying element and reclamping the free end thereof.

31. In a machine of the class described, the 50 combination with means for wrapping a tying element around a package and positioning portions in overlapping relation, of a combined clamp holder and crimper, a clamp former, means for transferring a formed clamp from the clamp former to said clamp holder, means for swinging 55 said clamp holder into position for receiving the overlapping portions of said tying element, means responsive to the movement of said clamp holder for guiding the overlapping portions of said tying element into the clamp in said holder, means for actuating said holder for crimping said clamp around the overlapping portions of said tying element, a rotatable member having spaced 60 radial blades for shearing the two outer strands 65 of the tying element and a clamping member responsive to the movement of said rotatable member for clamping the end of said tying element.

CERTIFICATE OF CORRECTION.

Patent No. 2,052,627.

September 1, 1936

WOLFGANG HERMANN.

It is hereby certified that error appears in the printed specification of the above numbered patent requiring correction as follows: Page 4, second column, line 3-4, claim 1, strike out the words "extending inwardly from one margin" and insert the same after "slot" and before the comma in line 2, same claim; and that the said Letters Patent should be read with this correction therein that the same may conform to the record of the case in the Patent Office.

Signed and sealed this 1st day of December, A. D. 1936.

Henry Van Arsdale

(Seal)

Acting Commissioner of Patents.
